194,543

COMBINED BUFFET TABLE AND SCREEN FOR PATIOS OR THE LIKE

William B. Martin, 261 Robbins St., Milton, Mass.

Filed June 28, 1960, Ser. No. 61,138

Term of patent 3½ years

(Cl. D33—1)

FIG. 4

FIG. 1

FIG. 2

FIG 5

FIG. 1 is a front elevational view of a combined buffet table and screen for patios or the like, showing my new design;

FIG. 2 is a side elevational view thereof;

FIG. 3 is a rear elevational view thereof;

FIG. 4 is a cross-sectional view thereof taken above line 4—4 in FIG. 1; and

FIG. 5 is a perspective view thereof with two of the screen members shown fragmentarily for illustrative purposes only.

The lining on the drawing represents contrast.

I claim:

The ornamental design for a combined buffet table and screen for patios or the like, substantially as shown and described.
